UNITED STATES PATENT OFFICE.

LEON LE PONTOIS, OF NEW ROCHELLE, NEW YORK, ASSIGNOR TO HURD & HAGGIN, A CORPORATION OF NEW YORK.

INDUCTOR MAGNETO ALTERNATOR.

No. 902,499.

Specification of Letters Patent.

Patented Oct. 27, 1908.

Application filed October 24, 1907. Serial No. 399,060.

To all whom it may concern:

Be it known that I, LEON LE PONTOIS, a citizen of the Republic of France, residing at New Rochelle, in the county of Westchester 5 and State of New York, have invented certain new and useful Improvements in Inductor Magneto Alternators, of which the following is a specification, reference being had to the accompanying drawings.

10 This invention relates in some features to alternating current magnetos especially designed for the generation of alternating current waves having rather sharp peaks and therefore best adapted to operate "spark-coils" used to effect ignition in internal combustion engines.

This invention relates more particularly to that type of magnetos called inductor alternators in which both the magnetic field structure 20 and the windings in which the alternating currents are generated are stationary, when in operation, the rotating element merely consisting of an iron armature having such a shape that it modifies by its rotation 25 the density and direction of the magnetic flux threading through the stationary windings. The intensity of such currents depends on the rate at which the density or direction of the magnetic flux through the generating wind- 30 ings is modified by the rotation of the inductor, and this depends in turn on the polar relation existing between the rotating element and the stationary element.

The special purpose of the present invention 35 is to change the density or direction of the magnetic flux more suddenly than in the devices heretofore used for this purpose, and this I have accomplished by providing a magnetic structure which secures a rapid change 40 in the density or direction of the magnetic flux through the generating windings during a relatively short period of time or during a small angular movement of the rotor. In order to obtain such results I employ the structure 45 illustrated in the drawings, in which

Figure 1 is an end view. Fig. 2, a vertical transverse median section. Fig. 3, a vertical longitudinal median section. Figs. 4, 5, and 6, show the paths of the magnetic flux 50 in different positions of the rotor.

The magnetic field is composed of a number of steel plates 1, 1, pressed into close contact by the frame 2, 2, and through bolts 3, 3. The frame and magnets are mounted in bear-

ings 7, 7, so as to be adjustable therein to 55 vary the time at which currents suitable for ignition purposes are generated.

Each of the plates 1 is magnetized by placing the surfaces of the two opposing central portions in close proximity respectively to 60 the north and south poles of a powerful electromagnet which closes its circuit through the V-shaped parts of the plate 1, developing in the central portions of the plates two consequent magnetic poles of opposite polarity. 65 The extensions N¹, N² of one central portion are therefore say of north polarity, while the extensions S¹, S² of the opposite central portion are of the opposite or south polarity. The polar extensions N¹, N² and S¹, S² are 70 connected respectively by bridges N³, S³ around which the generating windings 5, 6 are placed. The polar areas N¹, N², N³ and S¹, S², S³ are not permanently magnetized. The V shaped portions of the plates are 75 thoroughly hardened, while the central polar areas are allowed to remain comparatively soft by means of a special process.

In order to cause the steel molecules to assume permanently parallel positions in the 80 lines of magnetic polarization, in the V shaped portions the plates 1 are individually placed in close proximity to the magnetizing electro-magnet while they are at a high temperature, about 715° C. The V shaped ends 85 which are to be magnetized are then suddenly cooled while their molecules are under the influence of the magnetizing field. The central portions of the plates remain annealed, and when the plates are removed 90 from the influence of the electro-magnet, the V shaped parts of the plates only will be found to be permanently magnetized, while the central portions of the plates are magnetized by the inductive action of the permanently magnetized portions of the structure. By thus providing an integral plate 95 which is hardened and permanently magnetized in certain portions, while having soft portions of high permeability, I am enabled 100 to fulfil the objects of my invention without introducing the otherwise unavoidable reluctance of magnetic joints. I thereby obtain magnetic circuits of minimum reluctance and also secure great strength and rigidity in 105 the magnetic structure. In consequence of this condition of the plates 1, if a magnetic inductor, such as the rotor 4, be placed be-

tween N^2 , S^1 , as shown in Fig. 4, and is then suddenly changed to the position shown in Fig. 6, the magnetic flux will shift much more readily from the path N^2 , S^1 to the path 5 N^1 , S^2 than if the bridges N^3 , S^3 and polar extensions were not annealed.

The magnetic conditions corresponding to the different positions of the rotor 4 as illustrated in Figs. 4, 5 and 6 may be briefly described: In the position shown in Fig. 4 the 10 reluctance of the path N^1 , S^3 causes the flux which would otherwise issue from N^1 to cross the bridge N^3 and to pass by way of N^2 and the inductor 4, to S^1 and closing its circuit through the upper V , while the flux issuing from N^2 passes by way of 15 4, S^1 and S^3 closing its circuit through the lower V . In Fig. 6 owing to the great reluctance offered by the magnetic path N^2 , S^1 the magnetic flux instead of passing from N^2 crosses the bridge 20 N^3 and flows in parallel with the flux issuing from N^1 through the inductor and reaches the polar projection S^2 whence the two fluxes take divergent courses, one returning through 25 the lower V , the other returning through the bridge S^3 and the upper V to N^1 . In the position shown in Fig. 5, the magnetic reluctance of the paths N^1 , S^1 and N^2 , S^2 being practically equal, the magnetic flux tends to flow 30 through these paths, as shown by the arrows, closing its circuits through the upper and lower V polarized circuits respectively. Thus, while the inductor 4, occupies successively in its rotation the three positions 35 shown in Figs. 4, 5, and 6, the magnetic flux threading through the stationary windings, 5, 6, wound on the bridges, N^3 , S^3 passes from a maximum density in one direction to a maximum density in the opposite direction.

40 By reason of the exterior form of the plates 1, 1, and of the magnetic field composed of them, it is possible by means of rod 8 to swing the field magnets about their pivotal supports, so as to change the time of the 45 generation of the two high peaked current waves without causing the magnets to extend laterally beyond the central diameter, thereby permitting such change of position to be made within that space.

50 The circuit closer and interrupter is operated by a cam 10 on the rotor shaft and serves to short circuit the combined circuit of the two stationary windings 5, 6, excepting at or near the time when the current is 55 employed to produce a spark. When this circuit is opened the coils are placed in series with the primary of the induction coil and the electrical energy stored in them under the form of self induction is discharged to the 60 primary winding of the induction coil.

The electric circuit is opened at the moment when the current induced in the stationary windings reaches its maximum, and although this time varies slightly with the 65 increase of speed of the rotor it is approxi-

mately at the time when the rotor occupies the position shown in Fig. 6.

It will be noted that the dimensions of the polar faces of the rotating element in operative magnetic relation with the polar faces 70 of the stationary element are such that the total magnetic reluctance of the combined magnetic circuits changes very little in the different positions of the inductor when rotating within the stationary structure. This 75 is due to the width of the polar faces of the rotor being greater than the distance between adjoining polar extensions of the stationary element. Abnormal magnetic leakage which would otherwise lead to ultimate 80 demagnetization of the permanently magnetized portions, is consequently avoided. This arrangement also greatly increases the rapidity with which the intensity and direction of the flux threading through the generating windings changes and increases the intensity of the current generated in the windings correspondingly. Thus, it will be understood that, although the change in the density of the magnetic flux through the alternative paths successively controlled by 85 the rotor tends to correspond with the respective reluctance of said paths, yet by reason of the fact that the windings 5, 6 are short circuited upon themselves while the reluctance of the magnetic path is increasing, the current induced in the coils 5, 6 tends to oppose such change, and the rate at which the density of the flux decreases is not proportional to the increase in reluctance of the 90 magnetic path. Thus as the inductor passes from the position of Fig. 4, the reluctance of the path from N^2 to S^1 gradually increases; the density of the magnetic lines in said path does not decrease correspondingly however, 95 by reason of the current induced in the generating windings which tends to oppose such change, these windings being closed upon themselves at that time. A considerable portion of the inductor will therefore pass within 100 the influence of the polar extensions N^1 , S^2 before any great change in the density or path of the magnetic lines will take place. At the moment however, when the short circuit of the generating windings is removed 105 by the operation of the interrupter, the opposing action of the windings to change in flux is decreased, and at that moment a new path of low magnetic reluctance is offered to the flux by reason of a considerable portion 110 of the rotor having moved within the influence of the previously inactive polar extensions. The opposing action of the generating windings to change in flux having been decreased, and a new path of low magnetic 115 reluctance being simultaneously offered for causing the flux to pass through the windings in the opposite direction, the decrease in flux through the windings in the direction shown in Fig. 4 tends to coincide with the in- 120 125 130

crease of the flux in the opposite direction as shown in Fig. 6. The rapid change in flux through the generating windings which therefore results at the moment the short circuit of the windings is removed, leads momentarily to a comparatively large output of the generator during the short period required for energizing the sparking apparatus.

Although I have described one embodiment of my invention, it will be understood that various other embodiments and applications thereof may be made without departing from the scope of my invention. It will of course, also be understood that where I use the word "iron" in the claims, I intend to cover the use of steel as well, or any similar material.

I claim:

1. In a magneto generator of the inductor type, the combination of a frame comprising an integral member, said member having two permanently magnetized portions of hardened iron and portions of soft iron connecting poles of like polarity and integral with said permanently magnetized portions, windings on said soft iron portions, and a rotor for controlling the paths of the magnetic flux.
2. In a magneto generator of the inductor type, the combination of a frame comprising an integral member, said member having a permanently magnetized portion of hardened iron and a polar portion of soft iron integral therewith, a winding on said soft iron por-

tion, and a rotor for controlling the paths of 35 the magnetic flux.

3. In an inductor generator, the combination of a frame comprising a permanently magnetized portion of hardened iron and a polar portion of soft iron integral therewith, 40 a winding on said latter portion, and a rotating element for reversing the magnetic flux through said winding.

4. In a magneto generator, the combination of an element comprising a permanently 45 magnetized portion of hardened iron and a polar portion of soft iron integral therewith, a second element for controlling the path of the magnetic flux, and a winding on one of said elements.

5. In a magneto generator of the inductor type, the combination of a stationary frame comprising a plurality of iron parts, each of said parts having a plurality of permanently magnetized portions of hardened iron and a 55 plurality of portions of soft iron connecting adjoining poles of like polarity of said permanently magnetized portions and integral therewith, windings on said soft iron portions, and a rotating element for reversing 60 the direction of magnetic flux through said windings, said rotating element having polar faces of greater width than the space between like poles of said frame.

LEON LE PONTOIS.
